United States Patent Office

Des. 226,409
Patented Feb. 27, 1973

226,409

HANDBAG

Margaret Elizabeth Noone, 1901 Belfield Road,
Alexandria, Va. 22307

Filed Oct. 27, 1971, Ser. No. 193,242

Term of patent 14 years

Int. Cl. D3—01

U.S. Cl. D87—3 F

FIG. 1

FIG. 2

FIG. 3

FIG. 4

FIG. 1 is a front elevational view of a handbag showing my new design;

FIG. 2 is a rear elevational view thereof;

FIG. 3 is a side elevational view; and

FIG. 4 is a side elevational view of the side opposite that shown in FIG. 3.

I claim:

The ornamental design for a handbag, as shown.
